(57) CLAIM

The ornamental design for a candle holder, as shown and described.

DESCRIPTION

FIG. 1 is a perspective view of the candle holder;

FIG. 2 is a front view of the candle holder;

FIG. 3 is a back view of the candle holder;

FIG. 4 is a right side view of the candle holder;

FIG. 5 is a left side view of the candle holder;

FIG. 6 is a top plan view of the candle holder; and,

FIG. 7 is a bottom plan view of the candle holder.

As used in the drawings, the broken lines disclose the environment related to the claimed design and form no part of the claimed design.
